UNITED STATES PATENT OFFICE.

LOREN STAHL, OF CAREY, OHIO.

INSULATOR.

1,163,114.

Specification of Letters Patent.

Patented Dec. 7, 1915.

Application filed February 25, 1915. Serial No. 10,412.

To all whom it may concern:

Be it known that I, LOREN STAHL, a citizen of the United States, residing at Carey, in the county of Wyandot and State of Ohio, have invented certain new and useful Improvements in Insulators, of which the following is a specification.

This invention relates to insulators of the class known generally as cleats, for use in stringing and maintaining current carrying wires in suitably spaced relation with themselves and with the attaching walls.

The main object of the invention resides in the provision of a cleat wherein its sections are so formed that there is practically no possibility of them becoming disengaged when once they are in their applied position. It frequently happens that the various sections forming the cleat become dislodged or shifted in such manner that the wire or wires they are intended to support may also become dislodged.

A further object of the invention resides in so forming the structure that it is practically impossible for the current carrying wire or wires to so shift themselves that they come into engagement with the attaching nails or screws used for holding the insulator sections in position.

Other objects of the invention will appear after a further detailed description of the accompanying sheet of drawings representing the preferred embodiment of my invention.

In these drawings, similar characters of reference designate corresponding parts, and, Figure 1 represents a view in side elevation of the cleat, Fig. 2 is a top plan view of one of the sections, the sections being duplicates of each other, Fig. 3 is a side elevation of one of the sections shown detached, and, Fig. 4 is a detail view in perspective of one of the sections.

In the drawings, the cleat as a whole is represented by two similarly formed sections designated 1, these sections being formed so as to be interchangeable in order to render the selection of the coöperating parts to form a complete cleat, more handy. Each of these sections is provided with a pair of outstanding lugs 2, these lugs being preferably V-shaped in contour and extending transversely across each section approximately half its width, as shown. Each section is also provided with a pair of grooves

3 similar in shape to the lugs 2 in order that they may receive the opposing lugs of the other section in interfitting relation, these grooves, therefore, naturally forming the other half of the width portions of each section not occupied by the lugs 2. This arrangement of lugs and grooves prevents shifting of the insulator sections either in a longitudinal or transverse direction. Each section is also provided with a pair of nail attaching holes shown at 4, these holes being so located that they pass centrally through the intersections of the lugs and grooves of each section, this arrangement being followed to permit the complementary sections being made in true interchangeable order. Also, it is desirable to place these holes at the farthest possible point practicable from the transversely extending wire receiving grooves 5 and 1, therefore, locate these to pass through that side of the lugs 2 and grooves 3 nearest the section end faces as is indicated. Thus, it will appear that it is practically impossible for the wire to come into contact with the attaching nails even should the sections be so mounted that there would be a limited play between them.

In the use of the term "nail", it is understood that all such structures as are used for attaching cleats or insulators, are included.

It will thus be apparent that I have provided an insulator of peculiar construction so arranged that the various sections are prevented against shifting under any ordinary conditions. Also, these sections are made interchangeable in nature, which renders their selection in use comparatively easy. I desirably provide only one wire receiving groove for each section, this groove being located between the two nail receiving holes, but it is to be understood that if desired two or more wire receiving grooves may be provided.

What I claim is:

1. An insulator cleat comprising complementary superposed sections, each section being provided with a pair of depending lugs extending transversely across the section approximately half its width, the lugs of each section being located on opposite sides of the longitudinal center line of the section, each section being formed with a pair of grooves shaped to receive the opposing lugs of the

100

105

110

other section in interfitting relation, said grooves forming the other half of the width portions of said sections, and wire receiving formations between the lugs of each section.

- 5 2. An insulator cleat comprising complementary superposed sections, each section being provided with a pair of depending lugs extending transversely across the section approximately half its width, the lugs of each section being located on opposite sides of the longitudinal center line of the section, each section being formed with a pair of grooves shaped to receive the opposing lugs of the 10 other section in interfitting relation, said

grooves forming the other half of the width portions of said sections, and wire receiving formations between the lugs of each section, said sections being also formed with attaching nail holes passing centrally through the 20 intersections of the lugs and grooves of each section on the sides farthest from said wire receiving formations.

In testimony whereof I affix my signature in presence of two witnesses.

LOREN STAHL.
